CLAIM

The ornamental design for a heat exchanger, as shown and described.

DESCRIPTION

FIG. 1 is a perspective view of a heat exchanger showing our new design;

FIG. 2 is a top plan view of the design of FIG. 1;

FIG. 3 is a bottom plan view of the design of FIG. 1;

FIG. 4 is a front elevational view thereof of the design of FIG. 1;

FIG. 5 is a rear elevational view thereof of the design of FIG. 1;

FIG. 6 is a first side elevational view of the design of FIG. 1; and,

FIG. 7 is a second side elevational view of the design of FIG. 1.

1 Claim, 5 Drawing Sheets
